(57) CLAIM

The ornamental design for a speaker housing, as shown and described.

DESCRIPTION

FIG. 1 is a perspective view of a speaker housing showing my new design;

FIG. 2 is a front elevational view thereof;

FIG. 3 is a side elevational view thereof, the opposite side elevational view being a mirror image thereof;

FIG. 4 is a rear elevational view thereof; and,

FIG. 5 is a top plan view thereof, the bottom plan view being a mirror image thereof.

The broken line showings of the circular areas on the front are for illustrative purposes only and form no part of the claimed design.
